METHOBROMIDE AND HYDROCHLORIDE OF
1-ETHYL-3-PYRROLIDYL BENZILATE

Carl D. Lunsford, Richmond, Va., assignor to A. H. Robins Company, Inc., Richmond, Va., a corporation of Virginia

No Drawing. Filed May 16, 1960, Ser. No. 29,156

2 Claims. (Cl. 260—326.3)

This application is a continuation-in-part of Serial No. 666,250, filed June 17, 1957, now abandoned, and of Serial No. 795,598, filed February 26, 1959, and now Patent No. 2,956,062.

The present invention relates to esters of amino alcohols, more particularly certain esters of N- or 1-substituted 3-pyrrolidinols. These novel compounds are specifically identified as the N- or 1-substituted-3-pyrrolidyl benzilates. The concept constituting the present invention is illustrated by the following structural formula:

wherein R is a hydrocarbon radical, such as alkyl, cycloalkyl and aralkyl.

Nontoxic organic and inorganic acid addition salts of the compounds having the general structural formula shown above may be readily prepared as illustrated in the examples below and include salts formed with such inorganic and organic acids as hydrochloric, hydrobromic, hydriodic, sulfuric, sulfamic, phosphoric, acetic, glycolic, succinic, maleic, malic, citric, tartaric, ascorbic, benzoic, cinnamic, mandelic, benzilic, diphenylacetic and the like.

Quaternary ammonium salts such as alkyl salts cycloalkyl salts, aralkyl salts, and the like, of the organic bases illustrated in the general structural formula appearing above may be readily formed by treatment of the organic bases with the appropriate quaternary salt forming substances, which include, for example, methyl chloride, methyl bromide, methyl iodide, methyl sulfate, methyl benzenesulfonate, methyl p-toluenesulfonate, ethyl chloride, ethyl bromide, ethyl iodide, n-propyl chloride, n-propyl bromide, n-propyl iodide, isopropyl bromide, n-butyl chloride, n-butyl bromide, isobutyl bromide, sec.-butyl bromide, n-amyl bromide, n-hexyl chloride, benzyl chloride, benzyl bromide, and ethyl sulfate, yielding respectively the methochloride, methobromide, methiodide, methosulfate, methobenzenesulfonate, metho-p-toluenesulfonate, ethochloride, ethobromide, ethiodide, n-propochloride, n-propobromide, n-propiodide, isopropobromide, n-butochloride, n-butobromide, isobutobromide, sec.-butobromide, n-amobromide, n-hexochloride, benzochloride, benzobromide, ethosulfate, etc.

In the structural formula given above, the asterisk (*) serves to point out the asymmetric carbon atom present in the compounds of the invention. The two separate stereoisomers, or optically active forms, are included within the scope of the present invention. Resolution of the optically active forms may be accomplished by combining the mixture of stereoisomers with an optically active organic acid and separating by fractional crystallization.

Evaluation of the compounds of the invention by standard pharmacological tests has indicated their utility as inhibitors of gastrointestinal motility, comparing favorably in potency with methantheline bromide. The compounds are predominantly antagonists of acetylcholine.

The present invention is characterized by a particular esterification of a secondary hydroxyl attached directly to a ring carbon in the three position of the pyrrolidine ring. The prior art into which the compounds of the present invention fall can be distinguished. United States Patent 2,655,511 to Woodruff describes N- or 1-pyrrolidyl esters where the alkanol group is extra-cyclic to the pyrrolidine ring (where there is a methylene bridge attached to the heterocyclic nitrogen); United States Patent 2,695,301 to Blicke teaches benzilates proceeding from the two position of the pyrrolidine ring but differing from the present invention in that the hydroxyl esterified is primary and extra-cyclic; while United States Patent 2,735,847 to Blicke describes diphenylacetates proceeding from the N- or 1-position in the pyrrolidine ring and involves extra-cyclic esterification.

Therefore, it is an object of this invention to provide novel benzilates of 3-pyrrolidinols.

It is a further object of the present invention to provide such esters wherein the 3-pyrrolidine portion of the molecule is substituted in the N- or 1-position.

It is an additional object of the present invention to provide novel acetylcholine antagonists having a high degree of activity and satisfactory activity when compared with known compounds currently in use as inhibitors of gastrointestinal motility.

Other objects of the invention will become apparent to those skilled in the art to which this invention pertains.

The new compounds include the benzilates of 3-pyrrolidinols wherein the N- or 1-position of the pyrrolidine ring is substituted by a hydrocarbon radical such as straight or branched-chain alkyl, cycloalkyl, aralkyl and the like, preferably lower-alkyl.

The term lower-alkyl is defined to include straight and branched-chain radicals of 1-6 carbon atoms inclusive and includes such substituents as methyl, ethyl, isopropyl, tertiary butyl, isoamyl and the like. The term cycloalkyl is defined to include primarily cyclic alkyl radicals containing 5 to 8 carbon atoms inclusive and encompasses such substituents as cyclohexyl, cyclopentyl, methyl cyclohexyl, ethyl cyclopentyl, dimethyl cyclohexyl, and cycloheptyl. Included in the term aralkyl are such radicals as lower alkylsubstituted mono-carbocyclic aryl compounds such as benzyl, phenethyl, phenpropyl and the like. Preferably, R is a hydrocarbon radical containing less than 8 carbon atoms and is selected from the group consisting of lower-alkyl, cycloalkyl and aralkyl. On the other hand, the organic radical of the quaternary ammonium salts of the invention may be, for example any of the specific radicals, or types of radicals, e.g., lower-alkyl, cycloalkyl, or aralkyl, enumerated in this paragraph, the anion of the quaternary ammonium salt being, for example, halogen, e.g., chloro, nitro (NO₂), sulfate (SO₄), or any other anion enumerated in the preceding paragraphs of this specification relating to such quaternary salts.

Generally, for reasons of activity, the esters of this invention are preferred in the form of their nontoxic pharmaceutically acceptable acid addition and quaternary ammonium salts. Generally also, the N- or 1-lower-alkyl substituted compounds indicated greater activity and are therefore preferred. Among specifically preferred compounds are:

1-methyl-3-pyrrolidyl benzilate methobromide
1-methyl-3-pyrrolidyl benzilate hydrochloride
1-ethyl-3-pyrrolidyl benzilate hydrochloride, and
1-ethyl-3-pyrrolidyl benzilate methobromide.

Since the alpha carbon of the acetate group is substituted by a hydroxyl radical, the compounds may alternatively be viewed either as benzilates or phenyl-substituted

mandelates. The esters of the present invention may be prepared by reaction of a 1-hydrocarbon substituted-3-pyrrolidinol of the formula:

wherein R is as indicated above, with an alpha-phenyl-mandelic [benzylic] acid compound of the formula:

wherein B is hydroxy, halogen or lower-alkoxy.

When B is lower-alkoxy, the transesterification reaction is conducted in the presence of a sodium metal catalyst until the theoretical amount of lower alkanol separates. With this exception, the reaction conditions are similar for all variants of starting compounds, i.e., the reactants, used in approximately equimolar amounts, are heated at reflux temperatures for periods of at least about one hour and usually from one to two hours, preferably using a hydrocarbon solvent as the reaction media. The resulting reaction product is extracted with dilute mineral acid, e.g., hydrochloric acid, and the resulting extract basified (e.g., with aqueous sodium hydroxide) to yield the free base upon extraction with the appropriate solvent. The acid addition salts and quaternary salts are produced from the base by reaction in solvent of the base and the appropriate acid or quaternizing reagent.

The preparation of starting N-substituted-3-pyrrolidinols used in the present invention has been previously de-

The hydrochloride was precipitated from an ethereal solution of the base with ethereal hydrogen chloride and crystallized from a dry ethyl acetate-ethanol mixture; M.P. 191.5-193° C.

5 The methobromide quaternary salt precipitated from a butanone solution of the base and excess methyl bromide after standing for 24 hours. It was crystallized from a butanone-methanol mixture; M.P. 169-170.5° C.

10 In the same manner as given in the preceding example, by reacting the appropriate 1-hydrocarbon substituted-3-pyrrolidinol with the appropriate esterifying agent, additional compounds within the scope of the general structural formula are prepared.

15 Representative products prepared from the chosen starting materials are as follows:

- 1-phenethyl-3-pyrrolidyl benzilate hydroiodide
- 1-phenethyl-3-pyrrolidyl benzilate sulfate
- 1-phenpropyl-3-pyrrolidyl benzilate succinate
- 1-dimethylbenzyl-3-pyrrolidyl benzilate citrate
- 20 1-cycloheptyl-3-pyrrolidyl benzilate methobromide
- 1-phenethyl-3-pyrrolidyl benzilate tartrate
- 1-phenpropyl-3-pyrrolidyl benzilate benzoate
- 1-phenethyl-3-pyrrolidyl benzilate methochloride
- 25 1-phenpropyl-3-pyrrolidyl benzilate ethyl iodide
- 1-dimethylbenzyl-3-pyrrolidyl benzilate ethosulfate
- 1-phenethyl-3-pyrrolidyl benzilate
- 1-phenpropyl-3-pyrrolidyl benzilate methobenzene sulfonate.

30 Other compounds within the scope of the invention are shown in Table X. In each instance the free base as well as the indicated acid addition or quaternary salt was prepared.

TABLE X

R	Salt	Calculated for	Percent X	Found	M.W.	M.P., °C.
CH ₃	HCl	C ₁₀ H ₂₁ NO ₃ ·HCl	10.19	10.12	347.83	176-177

scribed in United States Patents 2,830,997 and 2,838,521 of Lunsford.

The following example illustrates the preparation of the compounds of the present invention, but is in no way to be construed as limiting:

All compounds may be prepared by the alternative modifications of the procedure using either the acid or acid chloride, or a lower-alkyl ester of the acid, e.g., methyl.

Example.—1-isopropyl-3-pyrrolidyl benzilate

A mixture of 72 grams (0.3 mole) of methyl benzilate and 39 grams (0.3 mole) of 1-isopropyl-3-pyrrolidinol in 400 milliliters of heptane was refluxed under a Dean and Stark moisture trap with the addition of four 0.1 gram pieces of sodium at one hour intervals. When the theoretical amount of methanol had separated, the solution was extracted with 3 N hydrochloric acid. The acid extract was basified with sodium hydroxide solution and extracted with ether. The ether layer was washed, dried over sodium sulfate and concentrated, and the residue fractionally distilled at reduced pressure. Yield: 55 grams (54 percent); B.P. 141-143° C. at 0.2 mm.

55 In evaluating the compounds of the invention pharmaceutically, the following experimental testing procedure was utilized.

Isolated guinea pig ileum studies

Guinea pigs were killed by a blow on the head. The ileum was removed and terminal segments were suspended in a 100 ml. smooth muscle bath containing Tyrode's solution which was maintained at 37° C. The bath was aerated by bubbling a continuous stream of oxygen therethrough. Intestinal activity was recorded by a balanced ink-writing lever yielding five-fold magnification on a Gorrell and Gorrell kymograph operated at speed P.

60 Aqueous solutions of all materials were employed in these studies. Essentially, the method consisted of initially standardizing submaximal contractions of the isolated ileum to acetylcholine chloride, histamine phosphate, serotonin creatinine sulfate, and barium chloride. The test material was then introduced into the bath and two minutes later the ileum was again challenged with the various spasmogens. Tests were made at various concentrations of the compounds in the bath until it was pos-

sible to differentiate their relative activity as antagonists of the spasmogens.

The results of the pharmacological testing indicate that the compounds are predominantly acetylcholine antagonists and are effective in inhibiting gastrointestinal motility in vivo and in vitro. In general, the compounds compared favorably in potency with methantheline bromide under the conditions of these tests.

Various modifications may be made in the compounds of the present invention without departing from the spirit and scope thereof, and it is to be understood that the invention is limited only by the scope of the appended claims.

I claim:

1. 1-ethyl-3-pyrrolidyl benzilate hydrochloride.
2. 1-ethyl-3-pyrrolidyl benzilate methobromide.
